UNITED STATES PATENT OFFICE

141,001

DESIGN FOR A MEMORIAL BANNER

Edward Spencer, Youngstown, Ohio

Application August 24, 1944, Serial No. 114,996

Term of patent 14 years

(Cl. D29—17)

To all whom it may concern:

Be it known that I, Edward Spencer, a citizen of the United States, residing at Youngstown, in the county of Mahoning and State of Ohio, have invented a new, original, and ornamental Design for a Memorial Banner, of which the following is a specification, reference being had to the accompanying drawing, forming part thereof.

In the drawing:

I claim:

The ornamental design for a memorial banner, as shown.

EDWARD SPENCER.
